(57) CLAIM

The ornamental design for a beverage container with motion sensitive LED-containing base.

DESCRIPTION

FIG. 1 is a perspective view showing the top and front of the beverage container of the present invention.

FIG. 2 is a side view thereof.

FIG. 3 is a top view thereof.

FIG. 4 is a bottom view thereof; and,

FIG. 5 is a perspective view indicating the emission of light by radial lines.
